WALL MOUNTED DISPLAY TRACK FOR TOY TRAINS

Jon W. Hauser II, St. Charles, Ill.

Application March 17, 1958, Serial No. 50,046

Term of patent 14 years

(Cl. D80—1)

Fig. 1 is a perspective view of a wall mounted display track for toy trains embodying my new design;

Fig. 2 is an enlarged end view thereof;

Fig. 3 is an enlarged top plan view thereof;

Fig. 4 is an enlarged front view thereof;

Fig. 5 is an enlarged back view thereof; and

Fig. 6 is an enlarged bottom plan view thereof.

A portion of the shelf is broken away in Figures 1 and 3 to 6, to indicate indeterminate length.

I claim:

The ornamental design for a wall mounted display track for toy trains, substantially as shown.
